(57) **CLAIM**

I claim the ornamental design for radiant lens, as shown and described.

DESCRIPTION

FIG. 1 is a front view of radiant lens embodying my new design.

FIG. 2 is a top view thereof.

FIG. 3 is a rear view thereof.

FIG. 4 is a bottom view thereof.

FIG. 5 is a left side view thereof.

FIG. 6 is a right side view thereof; and,

FIG. 7 is a cross-sectional view taken along line 7—7 in FIG. 1.

The broken line showing of environment is for illustrative purposes only and forms no part of the claimed design.
